(57) **CLAIM**

We claim the ornamental design for the bicycle frame, as shown and described.

DESCRIPTION

FIG. 1 is a perspective view of the bicycle frame from the left. FIG. 2 is a perspective view of the bicycle frame from above. FIG. 3 is the right side elevational view of the bicycle frame. FIG. 4 is the front elevational view of the bicycle frame. FIG. 5 is the left side elevational view of the bicycle frame. FIG. 6 is the rear elevational view of the bicycle frame. FIG. 7 is a top plan view of the bicycle frame; and, FIG. 8 is a bottom plan view of the bicycle frame. The broken lines illustrate unclaimed structure.
